FIG. 3

UNITED STATES PATENT OFFICE.

WALTER J. BARRON, OF NEW YORK, N. Y., ASSIGNOR, BY MESNE ASSIGNMENTS, TO UNION TYPEWRITER COMPANY, OF JERSEY CITY, NEW JERSEY, A CORPORATION OF NEW JERSEY.

TYPE-WRITING MACHINE.

1,030,453.

Specification of Letters Patent. Patented June 25, 1912.

Application filed August 23, 1910. Serial No. 578,539.

To all whom it may concern:

Be it known that I, WALTER J. BARRON, citizen of the United States, and resident of the borough of Brooklyn, city of New York, in the county of Kings and State of New York, have invented certain new and useful Improvements in Type-Writing Machines, of which the following is a specification.

10 My invention relates to paper feeding mechanism for typewriting machines and has for its principal object to provide improved releasing mechanism for releasing or throwing off from the platen the various paper feeding and controlling devices which coöperate therewith.

More specifically the object of my invention is to provide for throwing off or releasing at a single operation the main and secondary feed rollers, the paper deflector, the paper fingers and the card guide of a typewriting machine such as the No. 10 Remington typewriter; and also to provide for the release of the devices aforesaid at 25 a single operation without interfering with the usual releasing devices for the paper fingers which usual releasing devices operate separately and independently of each other and of the other devices aforesaid.

30 To the above and other ends my invention consists in the features of construction, combinations of devices and arrangements of parts hereinafter described and particularly pointed out in the claims.

35 My invention is shown as applied to a machine generally resembling the No. 10 Remington typewriter but various features of said invention may be adapted to other styles of writing machines.

40 In the accompanying drawings which show one form of my invention, Figure 1 is a fragmentary front elevation showing the platen and carriage of a No. 10 Remington typewriting machine, together with 45 various devices coöoperative with said platen and carriage. Fig. 2 is a fragmentary side elevation partly in section of Fig. 1. Fig. 3 is a view similar to Fig. 2 but omitting some of the parts shown therein and showing other parts in different relationships.

45 As shown in the various views, the platen frame or carrier comprises end plates 1 connected by a lower cross bar 2 and an upper cross rod 3. The end plates provide bear-

ings for a rotary cylindrical platen 4. The platen frame is mounted on a truck (not shown) and is adapted to shift up and down on said truck to change case, the shifting devices comprising a shift rail 5 on which runs a roller 6 mounted on the platen frame.

The platen is equipped with paper controlling devices which are preferably of the construction found in the No. 10 Remington machine. Said devices comprise both a main feed roller composed of sections 7 mounted on a shaft 8 and coöperate with the platen at the rear lower side thereof, and also a secondary feed roller comprising sections 9 mounted on a shaft 10 and coöperating with the platen at its forward lower side. The shafts 8 and 10 bear in the opposite arms of rocking levers or carriers 11, there being two such levers one at each end of the platen. Each lever 11 is pivoted at 12 to the forwardly extending arm 13 of a three-armed supporting lever, said supporting lever further comprising an upwardly extending arm 14 and a downwardly extending arm 15. Each three-armed lever is pivoted on a rod 16 which extends lengthwise of the machine and is secured near its ends to an L-shaped bracket comprising a forwardly extending arm 17 and an upwardly extending arm 18, the arm 17 terminating at its forward end in a downward extension 17^a which is secured by a screw 19 to the cross bar 2 underlying the platen. The arm 15 of each supporting lever has secured to it one end of a draw spring 20, the other arm of said draw spring being secured to the bar 2, the draw springs acting through the three-armed levers and the rocking levers 11, and serving normally to maintain the main and secondary feed rollers in co-operation with the platen or the paper thereon. Also pivoted on the rod 16 are forwardly extending arms 21 which pivotally support at 22 a paper deflector 23 which extends partly around the rear and under side of the platen between the two sets of feed rollers and is formed with openings for the feed roller sections.

The paper deflector is normally maintained in spring-pressed coöperation with the platen and is releasable by the arm 15, as shown in the No. 10 Remington machine. This construction of the paper deflector and

its mounting and the method of releasing said deflector by the arms 15 are not my invention and are not claimed *per se* by me. The mounting of the feed rollers 7 and 9, 5 and the method of releasing the same which will next be briefly described, are the invention of E. H. Berry as disclosed in his Patent No. 963,269, granted July 5, 1910. The bracket arms 18 extend upward at the 10 rear of the platen and are perforated at their upper ends to permit of the passage of a rock shaft 24 which bears at its ends in the bars or plates 1 of the platen frame. The rock shaft is manually controlled by 15 an arm or release key 25 fixed to it near its lefthand end and is also provided with a restoring spring 26 which coils around the rock shaft and is secured at its ends to pins 27 and 28 fixed respectively to the arm 25 20 and the lefthand end plate 1. Fixed to and depending from the rock shaft 24 are fingers 29 one behind each arm 14 and coöperative with said arms 14, when the release key is operated, to rock the three-armed levers 25 against their springs 20, thus releasing the feed rollers or moving them from the normal position (Fig. 2) to the abnormal position (Fig. 3). At the same time, as shown 30 in the machine, the paper deflector 23 is released. The springs 26 and 20 assist to restore the parts to normal position when backward pressure is removed from the release key.

Other paper controlling devices or paper 35 fingers coöperate with the platen at the front side thereof and are preferably like the paper fingers shown in the No. 10 Remington machine and in the pending application of George H. Smith, Serial No. 40 526,559, filed November 6, 1909. The paper fingers each comprise an upright portion or finger 30 of sheet metal preferably, said finger carrying at its upper end a pressure roller 31 which coöperates with the 45 front of the platen above the printing line, which is along the middle of the front face. At its lower end each finger is broadened by a lateral off-set 32 and is curled or bent around a rectangular rock shaft 33. There 50 are two rock shafts one for each paper finger so that the paper fingers may be separately released. Each rock shaft 33 bears at its outer end in the adjacent end bar 1 of the platen frame and at its inner end in a bearing opening formed at the top of an upright arm 34 comprised in a U-shaped supporting bracket. There are two 55 arms 34 spaced apart and connected at their lower ends by a cross bar 35, the two arms 34 and the arm 35 constituting said supporting bracket which is secured to the front bar 2 of the platen frame by screws 36. The paper fingers are slidable along their respective supports or rock shafts 33 to coöperate 60 with paper of different widths and each

rock shaft is manually controlled by a key or arm 37 which is secured to the end of its associate rock shaft 33 outside the adjacent end bar 1. The arms 37 extend horizontally rearward and each is connected to a vertical draw spring 38 which is also connected with a lug 39 on the adjacent end bar 1. The draw springs 38 tend constantly to pull the arms 37 downward and rock the shafts 33 rearward so as to maintain the pressure rolls 31 in spring-pressed coöperation with the platen or the paper thereon. Each arm 37 is provided with an upwardly and forwardly extending finger piece or key 40 which on being pressed downward overcomes the associate spring 38 and rocks the shaft 33, thus releasing the associate pressure roll 31, moving the same from normal position (Fig. 2) away from the platen to the position shown in Fig. 3.

The main and secondary feed rollers and the paper fingers, it will be observed, are mounted on the platen frame or carrier and travel with the platen during its letter spacing movements. The No. 10 Remington machine is further equipped with a relatively stationary paper controlling or guiding device or card guide 41 which comprises downwardly extending flexible arms 42, said arms being secured by screws 43 to a bracket 44 fixed to the shift rail 5. It will be seen that the device 41 remains stationary during the letter space movements of the platen, always bearing the same relation with respect to the printing point. The device 41 is 100 not my invention and is not claimed *per se* by me.

As thus far described and as shown in the machine, the releasing of the feed rollers and paper deflector does not affect the paper 105 fingers nor the card guide while on the other hand the releasing of either paper finger 30 does not affect the other paper finger nor any of the paper controlling devices aforesaid. No provision is made in the machine 110 for releasing the card guide 41 other than by pulling it away by hand from the face of the platen. In practice it is sometimes desirable to simultaneously release all of the paper controlling devices above named so 115 that a free and unobstructed way for the paper may be afforded all the way around the platen. By my invention I provide for simultaneously releasing all the paper controlling devices and this I accomplish without 120 affecting the devices heretofore provided for separately releasing certain of said devices.

My invention as shown in the present instance comprises a bar or rod 45 which extends lengthwise of the machine forward of the platen, said bar 45 being arranged above the rock shafts 33 and behind the paper fingers and card guide. The bar 45 is provided near its ends with tabs or ears 46 130

which bear on rounded portions 33^a of the rock shafts 33, thus providing a pivotal mounting of said rod 45 on the rock shafts. The bar 45 is angular in cross section as shown in Fig. 3 and is adapted to coöperate with the back of the card guide 41 and with the backs of depressions 30^a formed in the paper fingers 30. Through such coöperation the paper fingers and card guide are adapted to be simultaneously released or swung away from the platen to the positions shown in Fig. 3. In order to turn the bar on its pivot to effect such release of the paper fingers and card guide, it may be pulled forward by hand, but preferably I provide devices which are controlled automatically preferably from the release key 25, so that by the operation of said release key the feed rollers 7 and 9 at the under side of the platen are released and at the same time the devices 31 and 41 at the front of the platen are released. The releasing devices for the bar 45 comprises extensions or fingers 47 which curve rearward and downward from the ends of said bar 45. As shown in Fig. 1 the bar 45 extends at its ends beyond the end plates 1 and the fingers 47 are outside said end plates. The weight of the extensions tends normally to turn the bar 45 rearward but said bar is maintained in normal position by stop pins 48 which project laterally inward from the end plates 1 and coöperate with the rear sides of the ears 46. The ends of the fingers 47 are rounded and are adapted to be engaged by the forward end portion of releasing arms 49, of which there are two. Said arms are secured to the outer ends of the rock shaft 24 by screws 50. The releasing arms 49 are arranged outside the adjacent end plates 1 and extend downward and forward, being normally separated from their associate fingers 47 as shown in Fig. 2.

When the release key 25 is pressed rearward, rocking the shaft 24 and releasing the feed rollers 7 and 9, the rock shaft 24 as it turns, rocks the releasing arms 49 upward and toward the end of its turning movement said arms are brought into contact with the fingers 47. After such contact said arms 49 during further movement swing the fingers 47 upward and rock the releasing bar 45 forward on its pivot. The forward movement of the bar 45 brings it into operative contact with the paper fingers 30 and card guide 41, said bar thus acting to release the paper fingers and pressure rolls 31 and to swing the card guide 41 to the released position shown in Fig. 3, the flexible fingers 42 yielding sufficiently to permit of this movement of the card guide. When pressure on the key 25 is released the card guide is restored by the inherent spring of the arms 42, and the pressure rollers 31 are restored by the springs 38; while, of course, the main

and secondary feed rollers and paper deflector are returned in the usual way.

It will be seen that by the use of my invention all the paper controlling devices including the main and secondary feed rollers, paper deflector or apron, paper fingers and card guide may be swung away from the platen or released at a single operation, thus providing a clear passage around the platen for the paper.

It will be observed further that by my present invention I provide for automatically releasing the paper fingers simultaneously, the automatic means in the present instance comprising connections between the releasing bar 45 and the rock shaft 24, said rock shaft being operative by the key 25 and carrying releasing devices for the main and secondary feed rollers, the main feed roller in the present instance being at the introductory side of the platen, that is, at the lower rear side thereof, while the secondary feed roller is arranged below the printing point and between the same and the main feed roller. The release key 25 also operates to turn the two rock shafts 33 automatically to release the paper fingers and also operates to release automatically the paper guiding device or card guide 41, the means by which this automatic release is effected in the present instance being the releasing bar 45. It is further to be noted that the two rock shafts 33 may be turned independently of each other to release their associate paper fingers and that this independent turning of the rock shafts is also independent of the releasing bar 45 and of the releasing mechanism for the feed rollers.

By my present invention I provide simple and effective means for completely freeing the platen from the various paper controlling and feeding devices which normally coöperate with said platen; and said means have been applied to the machine in the present instance without interfering with the normal operation of the other devices with which the machine has been hitherto equipped.

Various changes may be made without departing from the spirit and scope of my invention.

What I claim as new and desire to secure by Letters Patent, is:

1. In a typewriting machine, the combination of a platen, a feed roller, releasing means for said feed roller, a plurality of paper fingers, key controlled devices for releasing said paper fingers separately and independently of each other, said paper fingers being adjustable independently of said devices, and automatic means for releasing said paper fingers simultaneously.

2. In a typewriting machine, the combination of a platen, a plurality of paper fingers coöoperative therewith, key controlled de-

5 vices for separately and independently releasing said paper fingers, said paper fingers being adjustable independently of said devices, and key controlled means for releasing said paper fingers simultaneously.

3. In a typewriting machine, the combination of a platen, a feed roller, releasing means for said feed roller, a plurality of paper fingers, key controlled devices for releasing said paper fingers separately and independently of each other, said paper fingers being adjustable independently of said devices, mechanism for releasing said paper fingers simultaneously, and connections between said mechanism and said feed roller releasing means for simultaneously releasing said paper fingers when said releasing means is operated.

4. In a typewriting machine, the combination of a platen, a feed roller, key controlled devices for releasing the same comprising a rock shaft; a paper finger adjustable lengthwise of said platen, a releasing bar for said paper finger extending transversely thereof and lengthwise of said platen, said paper finger being mounted independently of said bar, and means connected with said rock shaft for operating said releasing bar.

5. In a typewriting machine, the combination of a platen, a feed roller, key controlled devices for releasing the same comprising a rock shaft; a paper finger adjustable lengthwise of said platen, a pivoted releasing bar for releasing said paper finger, and an arm fixed to said rock shaft and operative on said releasing bar.

6. In a typewriting machine, the combination of a platen, a feed roller, key controlled devices for releasing the same comprising a rock shaft; a paper finger adjustable lengthwise of said platen, a releasing bar extending lengthwise of the platen behind said paper finger, said releasing bar being pivoted near its ends, and means on said rock shaft for pivotally turning said bar to release said paper finger.

7. In a front-strike typewriting machine, the combination of a platen, a feed roller at the introductory side thereof, releasing means for said feed roller, a paper finger cooperative with said platen at the front thereof and adjustable lengthwise of said platen, a bar extending lengthwise of said platen below the printing point and arranged between said platen and said paper finger, and connections between said bar and said releasing means operative to actuate said bar to release said paper finger.

8. In a typewriting machine, the combination of a platen, main and secondary feed rollers cooperative with said platen, a paper deflector extending partly around said platen between said main and secondary feed rollers and releasable therewith, means

for releasing said feed rollers, a plurality of paper fingers, key controlled devices for separately and independently releasing the same, and means connected with said releasing means for releasing said paper fingers simultaneously.

9. In a typewriting machine, the combination of a platen, main and secondary feed rollers coöoperative with said platen, a paper deflector extending partly around said platen between said main and secondary feed rollers and releasable therewith, means for releasing said feed rollers, a plurality of paper fingers, key controlled devices for separately and independently releasing said fingers, a card guide independent of said paper fingers, and means connected to said releasing means for simultaneously releasing said paper fingers and said card guide.

10. In a typewriting machine, the combination of a platen, main and secondary feed rollers coöoperative with said platen, a paper deflector extending partly around said platen between said main and secondary feed rollers and releasable therewith, means for releasing said feed rollers, a plurality of paper fingers, key controlled devices for separately and independently releasing the same, a card guide independent of said paper fingers, and a pivoted bar extending lengthwise of the platen and operative by said releasing means to simultaneously release said paper fingers and said card guides.

11. In a front-strike typewriting machine, the combination of a platen, a main feed roller at the introductory side thereof, a secondary feed roller arranged below the printing point and between the printing point and the main feed roller, a paper deflector between said feed rollers and releasable therewith, a plurality of upright fingers each carrying a pressure roll coöoperative with the platen above the printing point, key controlled devices for separately releasing said pressure rolls, said rolls being adjustable independently of said devices, releasing means for said feed rollers, and means connected with said releasing means for simultaneously releasing said pressure rolls.

12. In a front-strike typewriting machine, the combination of a platen frame, a main feed roller at the introductory side thereof, a secondary feed roller between the printing point and the main feed roller, a paper deflector between said feed rollers and releasable therewith, a plurality of pressure rolls coöoperative with the platen above the printing point, key controlled devices for separately releasing said rolls, a card guide mounted independently of said platen frame, said feed rollers, deflector and pressure rolls being mounted on said platen

- frame, and means for simultaneously releasing said feed rollers, pressure rolls and card guide.
13. In a typewriting machine, the combination of a platen frame, a platen thereon, a paper finger on said platen frame, a paper guiding device mounted independently of said platen frame, and means for simultaneously releasing said paper finger and said guiding device.
14. In a front-strike typewriting machine, the combination of a platen frame, a platen thereon, a plurality of paper fingers adjustable lengthwise of said platen and co-operative therewith at the front side of said platen, a paper guiding device mounted independently of said platen frame, and means for simultaneously releasing said paper fingers and said guiding device.
15. In a front-strike typewriting machine, the combination of a platen frame, a platen thereon, a plurality of paper fingers adjustable lengthwise of said platen and co-operative therewith at the front of said platen, a paper guiding device mounted independently of said platen frame, means for simultaneously releasing said paper fingers and said guiding device, and means for releasing said paper fingers independently of said guiding device.
16. In a front-strike typewriting machine, the combination of a platen frame, a platen thereon, a plurality of paper fingers adjustable lengthwise of said platen and co-operative therewith at the front of said platen, a paper guiding device independent of said platen frame, means for simultaneously releasing said paper fingers and said guiding device, and key controlled means for releasing each of said paper fingers separately and independently of each other, and also independently of said guiding device.
17. In a typewriting machine, the combination of a platen frame, a platen thereon, a plurality of rock shafts on said platen frame, key controlled devices for separately turning said rock shafts, paper fingers mounted for adjustment along each of said rock shafts, and means for releasing said paper fingers simultaneously.
18. In a typewriting machine, the combination of a platen frame, a platen thereon, a plurality of rock shafts on said platen frame, key controlled devices for separately turning said rock shafts, paper fingers mounted for adjustment along each of said rock shafts, and means for simultaneously releasing said paper fingers, said releasing means comprising a bar extending longitudinally of the platen behind said paper fingers.
19. In a typewriting machine, the combination of a platen frame, a platen thereon, a plurality of rock shafts on said platen frame, key controlled devices for separately turning said rock shafts, paper fingers mounted for adjustment along each of said rock shafts, a feed roller, releasing means for said feed roller, and means connected with said releasing means for simultaneously releasing said paper fingers.
20. In a typewriting machine, the combination of a platen frame, a platen thereon, adjustable paper fingers, a plurality of rock shafts on said platen frame, each shaft supporting certain of said fingers, key controlled devices for separately turning said rock shafts, a feed roller, releasing means for said feed roller, and means connected with said releasing means for simultaneously releasing said paper fingers, said last recited means comprising a releasing bar extending lengthwise of the platen and pivoted on said rock shafts.
21. In a typewriting machine, the combination of a platen frame, a platen thereon, a plurality of rock shafts on said platen frame, key controlled devices for separately turning said rock shafts, paper fingers mounted for adjustment along each of said rock shafts, a feed roller, releasing means for said feed roller comprising a manually operated shaft, a releasing bar extending lengthwise of the platen behind said paper fingers and pivoted on the rock shafts carrying said paper fingers, and arms fixed to said manually operated shaft and adapted to actuate said releasing bar.
22. In a front-strike typewriting machine, the combination of a platen frame, a platen thereon, a plurality of rock shafts on said platen frame, paper fingers adjustable on said rock shafts, key controlled devices for separately turning said rock shafts to separately release said paper fingers, a feed roller, releasing means therefor, and a releasing bar for simultaneously releasing said paper fingers through connections with said releasing means, said releasing bar being independent of said key controlled devices.
23. In a front-strike typewriting machine, the combination of a platen frame, a platen thereon, a plurality of rock shafts on said platen frame, paper fingers adjustable on said rock shafts, key controlled devices for separately turning said rock shafts to release certain of said paper fingers independently of other of said fingers, a feed roller, releasing means therefor, a releasing bar for simultaneously releasing said paper fingers through connections with said releasing means, said releasing bar being independent of said key controlled devices, and a paper guiding device mounted independently of said platen frame and releasable by said releasing bar.
24. In a typewriting machine, the combination of a platen, a carriage, a paper guid-

ing device comprising a flexible supporting arm fixedly secured to a part independent of said carriage, and a key controlled bar operative on said supporting arm to release 5 said guiding device from coöperation with said platen.

Signed at Hingham, in the county of

Plymouth and State of Massachusetts this
19th day of August A. D. 1910:
